UNITED STATES PATENT OFFICE

107,391

DESIGN FOR A DRESS

Ida Lampel, New York, N. Y.

Application November 6, 1937, Serial No. 72,648

Term of patent 3½ years

To all whom it may concern:

Be it known that I, Ida Lampel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the application and particular arrangement of the lace units on the net dress, as shown.

I claim:

The ornamental design for a dress, substantially as shown, and described.

IDA LAMPEL.
